Claims priority, application Great Britain, June 28, 1962, 24,879/62

3 Claims. (Cl. 313—61)

This invention relates to neutron generators of the type in which an ion source generates ions which are accelerated across an acceleration gap by a potential difference applied across the gap, so as to strike a target material with high energy, the ion source and the acceleration gap being within a common sealed envelope at substantially the same pressure. It is necessary to have a short well-defined acceleration gap so as to keep the conditions well up the left hand side of the Paschen curve relating breakdown voltage to the product of the gas pressure and the acceleration distance.

In such generators the gas pressure is normally within the range $1 \text{ to } 1000 \times 10^{-4}$ mm. pressure and the voltage across the acceleration gap is normally 10–200 kv.

Much information on neutron generators is available in published form and attention is directed to Review of Scientific Instruments, 31 (1960) 3 and to Nucleonics, vol. 18, No. 12, December 1960, pages 69–76 which give descriptions of some sealed-off neutron generators.

In the calibration of neutron generators employing the DT reaction, it is customary to count the 3.5 m.e.v. alpha particle from the reaction $T + D \rightarrow \alpha + n + 17.6 \text{ m.e.v.}$ Alpha particles are, however, easily absorbed by even thin solid materials and the counting of alpha particles through the sealed envelope of sealed-off neutron generators is impossible. A thin window for passage of alpha particles through the envelope would be so thin that it would be too fragile and could not stand normal handling.

This invention provides a neutron generator of the type specified having an alpha particle counter inside the sealed envelope.

The invention consists in a neutron generator of the type specified in which an electrostatic shield is positioned between the target and the ion source to provide one boundary of the acceleration gap and maintain a field-free zone within which the target is located, said shield having an aperture for passage of ions from the ion source to the target, and a detection means for detecting alpha particles emitted by the target is mounted within the said field-free zone in direct view of the target.

In this way Paschen breakdown between the alpha counter and the ion source is prevented, and secondary electrons given off by the target cannot attain full acceleration potential and impinge on the counter.

An embodiment of the invention is illustrated by way of example in the accompanying drawing which is a diagrammatic general assembly.

In the drawing a sealed glass envelope 1 has an arm 2, containing a deuterium replenisher 3 as described in the first of the above references, and an arm 4 containing a Pirani pressure gauge 5. A tritium loaded target 6 is mounted within a metal cylindrical shield 7 by means of brackets 8 and 9. A mesh 10 provides an aperture for ions directed at the target. Cylinder 7 is supported on electrodes 11. A solid-state alpha counter 12 is mounted in a metal shield can 13 having an aluminium foil window 14, the window being opposite a port in cylinder 7 and being in full view of the target 6.

The can reduces pick up from plasma oscillations in the ion source and from R.F. waves originating in power supplies. The aluminium foil window (0.9 mgm./cm.²) al-

2

lows entry of the alpha particles but stops light and ions elastically scattered from the target.

A cathode 15 has a heater 16 both supported by their stiff wire connections 17 and 18 respectively. A tubular anode 19 is supported on its connection 20. An extractor cathode 21 has a mesh 22 opposite the mesh 10, the distance between the two meshes constituting an acceleration gap.

A coil not shown, applies an axial magnetic field to the space between cathodes 15 and 21.

With the geometry shown, the number of alpha particles counted is about $\frac{1}{200}$ of the total.

To operate the tube, the target and alpha counter are held at earth potential and a positive voltage of 60 kv. is applied to the extractor cathode, the anode voltage being about 70 v. higher. With gas pressure of 20 microns and an axial magnetic field of 200 gauss, the ion source current was 0.5 to 1 ma., providing an ion current of 5 to 10 ma. molecular ions.

Alpha counter bias was 15 v. and amplified pulses can be fed to a multi-channel analyser and a timed scaler.

The alpha counter used in one embodiment was made by diffusing phosphorus into 3000 ohm p-type silicon. Electrical connection to the phosphorus diffused surface was made by using a silver paste as a glue for a fine wire.

We claim:

1. A neutron generator comprising a sealed envelope containing an electrostatic shield positioned between a target and an ion source to form one boundary of an accelerating gap and to provide a field-free zone on the side of the shield remote from the ion source, said target being located within said zone, said shield having an aperture for passage of ions from the ion source to the target, and means mounted in direct view of the target for detecting alpha particles emitted by the target, said detecting means being mounted within said field-free zone on the side of the shield remote from the ion source to prevent secondary electrons emitted from the target from being accelerated towards the detecting means.

2. A neutron generator as claimed in claim 1 wherein the detecting means is a solid-state alpha-counter located behind a window which allows the entry of alpha particles to the counter while preventing the entry of light thereto.

3. A neutron generator as claimed in claim 1 wherein the electrostatic shield is a tube, said aperture for passage of ions from the ion source being at one end of the tube and of smaller diameter than the tube, said target being mounted within said tube at an angle to the direction of the ion beam and said detecting means being mounted in a side-arm sealed to the envelope, a port being provided in the wall of the tube to allow alpha particles from the target to reach the detector.
